UNITED STATES PATENT OFFICE.

SIGMUND GICZEWSKI, OF HAMMOND, INDIANA.

DOOR HANGER.

1,403,764.

Specification of Letters Patent. Patented Jan. 17, 1922.

Application filed April 20, 1921. Serial No. 462,852.

To all whom it may concern:

Be it known that I, SIGMUND GICZEWSKI, a citizen of the United States of America, and resident of Hammond, in the county of Lake and State of Indiana, have invented 5 certain new and useful Improvements in Door Hangers, of which the following is a specification.

This invention relates to car doors and 10 particularly to means for holding the car door against movement when it is either in an open or a closed position, so that unauthorized persons cannot manipulate the door or impair it by moving it backward 15 and forward.

An object of this invention is to produce a door primarily for box cars although, of course, it may be used in connection with other closures.

20 A further object of this invention is to produce means for suspending a sliding door, whereby one of the suspending elements may be utilized as a means for locking it, thus making it possible to produce an 25 efficient lock having comparatively few parts of inexpensive construction.

With the foregoing and other objects in view, the invention consists in the details of construction, and in the arrangement and 30 combination of parts to be hereinafter more fully set forth and claimed.

In describing the invention in detail, reference will be had to the accompanying drawings forming part of this application 35 wherein like characters denote corresponding parts in the several views, and in which—

Figure 1 illustrates a view in elevation of a fragment of a box car with a device embodying the invention applied thereto;

Figure 2 illustrates a sectional view on an enlarged scale on the line 2—2 of Fig. 1;

Figure 3 illustrates a sectional view on the line 3—3 of Fig. 1;

45 Fig. 4 illustrates an enlarged detail of the locking mechanism; and

Fig. 5 illustrates a perspective view of the rail.

In these drawings, 10 denotes a fragment 50 of a box car having the usual door opening 11 to be closed by a door 12. The car body has the usual guiding members such as 13 which are here conventionally shown.

The door rail or track 14 has apertures 55 or seats 15 formed therein for a purpose to be presently explained, and it has an anchor-

ing flange 16 with apertures 17 to receive the fastenings 18 such as bolts or rivets, by which the track is supported, and the said track has a depending flange 19 which operates as a guide for the upper edge of the door.

Hanger brackets 20 and 21 are anchored to the door near its upper edge and they project thereabove. The bracket 20 has a 60 wheel 22 rotatably mounted on it, and the configuration of this bracket is well shown in Fig. 3. The bracket 21 is of the same general contour as the bracket 20, but the offset portion 23 thereof has an aperture 65 24 therethrough, through which an operating element 25 such as a rod may project. The door may also be provided with a guide 26 in which the operating element 25 may slide. A toothed wheel 27 is rotatably 70 mounted in the bracket 21 and it acts as a combined traction or supporting wheel and one of the locking elements by which the door is held at different positions of adjustment, it being understood that the teeth 28 75 of the wheel will enter the apertures or seats 15 in the rail as it rotates during the opening and closing of the door. The fact that the teeth of the wheel are successively seated in the recesses renders it possible to prevent 80 movement of the door if the wheel is prevented from rotating. To that end, a dog 29 is pivotally mounted in the bracket 21 in such position that its nose will engage the teeth of the wheel and prevent rotation 85 of the wheel so long as the dog is in said engagement. Means are provided for swinging the dog on its pivot into and out of operative relation to the wheel, and to that end, the member 25 is connected to the dog so 90 that by thrusting the said member upwardly, the dog is moved out of engagement with the wheel, whereas when it is released or permitted to move downwardly, the said toothed wheel will be locked against 95 rotation, and hence, the door cannot be moved.

As a means for operating the member 25, a sectional handle 30 has a joint 31 by which one section can be moved with relation to the other, and this sectional handle has one end 105 oscillatable on a pivot 32 which projects from the outer face of the door, as in this embodiment of the invention, one part of the sectional handle also has an apertured loop 33 which is intended to receive a staple 34 110 likewise anchored to the door, and this staple may have a securing device 35 inserted in it

after the sectional handle has been applied to the staple, and thus the sectional handle will be held against movement. Of course in this connection, a car seal or lock may be employed as a substitute for the fastening 35, and hence, when a car door is once locked, it cannot be released except through the manipulation of the handle. When a person is desirous of opening or closing the door, the removal of the sectional handle from the staple and an upward oscillation of the said handle, will result in lifting the dog from engagement with the teeth of the wheel and the door can then be moved to an open or closed position by pulling on the handle, after which the said sectional handle may be re-set in the locked position to hold the door against movement and of course this operation may be repeated as desired.

20 I claim:

1. In a lock for sliding doors, a track having seats therein, a door having brackets extending thereabove, a toothed wheel rotatably mounted with relation to one of the brackets and engaging the seats of the track, a dog pivotally mounted on the said bracket and adapted to engage the teeth of the wheel for holding it in adjusted position, a member

connected to the dog for operating the same, a sectional handle pivotally mounted on the door to which the said dog operating member is connected, and means for holding the sectional handle against movement when the dog is in engagement with a tooth of the wheel. 35

2. In a closure for car doors and the like, a track having seats therein, a door having brackets, wheels rotatably mounted in the brackets and adapted to travel on the track, teeth on one of the wheels adapted to enter the recesses in the track, a dog pivotally mounted on the bracket and adapted to engage the teeth of the wheel for holding the wheel against rotation, a member connected to the dog and operative to lift the same from engagement with the teeth of the wheel, a sectional handle to which the member is connected, means for pivoting the sectional handle in operative relation to the door, the said sectional handle having an aperture therein, 50 a staple to which the apertured handle is applied, and means extending through the staple for locking the sectional handle against movement.

SIGMUND GICZEWSKI.
